UNITED STATES PATENT OFFICE.

JOHN H. BURKHOLDER, OF ASHLAND, OHIO.

LIFTING-JACK.

No. 850,209.

Specification of Letters Patent.

Patented April 16, 1907.

Application filed December 31, 1906. Serial No. 360,138.

To all whom it may concern:

Be it known that I, JOHN H. BURKHOLDER, a citizen of the United States, residing at Ashland, in the county of Ashland and State 5 of Ohio, have invented certain new and useful Improvements in Lifting-Jacks, and do declare that the following is a full, clear, and exact description of the invention, which will enable others skilled in the art to which 10 it appertains to make and use the same.

My invention relates to lifting-jacks; and the invention consists in a lifting-jack which is intended more particularly for automobiles and like heavy vehicles and in which 15 both speed of adaptation and power in operation are desirable.

In the accompanying drawings, Figure 1 is a side elevation of my improved lifting-jack, and Fig. 2 is a central sectional elevation thereof. Fig. 3 is a cross-section on the line of the pivot of the operating-handle; and Fig. 4 is a side elevation, partially in section, of the means for reversing the direction of 20 operation either up or down, as may be required.

A represents the standard of the jack, having a suitable base and tubular or hollow from end to end and adapted to receive and operate lift member B. Said member is 25 shown as inserted from the top of the standard and threaded in its body downward to its lower end and carries a guide-pin 2, adapted to run in a channel or groove 3 in standard A in order to keep head 4 of the said lift 30 member in right working relations at all times with the other parts and prevent member B from turning. The said member B has threaded miter-gear C mounted thereon in a recess in the standard between lateral 35 supporting and connecting arms 5, which unite the top portion of the standard with the body thereof about the said recess. The weight coming on the said lift member rests 40 on the standard through said bevel-gear C, and the said gear is meshed and actuated 45 through the compound bevel and spur gear D, supported on the side of the standard A on short shaft or spindle d and upon which said gear D is free to be rotated either way, 50 according to the direction of movement to be given lift member B.

H represents the operating or power handle, which is loosely pivoted upon short shaft d behind bevel-gear D or between the 55 same and standard A and in itself is wholly independent of all the associated parts, but

carries a double-armed pawl J, pivoted at its middle in the side of said handle and adapted to engage gear D, and said gear is in such relation thereto as to permit either arm or 60 extremity of the pawl to be thrown into engagement with the teeth of said gear, according as rotation is to be had in one direction or the other. For example, if upper arm 6 be in engagement the gear will be rotated in one 65 direction, and if the lower arm 7 be in engagement the gear will be operated in the opposite direction, and the said pawl is adapted to swing on its pivot and to be held in either engaging position by means of spring 8, located behind the same in a socket in handle H and engaged centrally with the pawl at 9. It follows that if the pawl be thrown either 70 way the spring will hold it in that position until it be reversed by hand, and the pawl is 75 adapted to be engaged at its upper end 6 by the finger and held out of engagement with gear D temporarily in order that said gear may be rotated by hand to quickly bring lift member B to proper elevation for use, 80 thus saving time which would be required to operate the said member more slowly by lever or handle H. To this end the said gear has a crank-handle 10 on its side, and the operator need simply withdraw the pawl and 85 turn the gear by this handle to raise or lower the lift member with speed and ease. Then having gotten the desired elevation of the lift member the pawl J is thrown into suitable engagement and further operations are 90 by lever H.

In the present organization the jack is raised by raising the handle, but it may be reversed as to this and made to raise or lift when the handle is depressed. By locating the 95 pivot of the handle inside of gear D, I am enabled to give the gear its own free rotation by its handle 10 in order to get the quick elevations above referred to.

Gear D has been referred to as having compound teeth, the same being beveled at d' to mesh with gear C and straight in their outer portions d'' to be engaged by pawl J, thus serving as ratchet-teeth in connection with said pawl.

What I claim is—

1. A lifting-jack having a standard with a vertical guideway inside and a recess in its upper portion and having the top of the standard above the said recess and supported by arms 5, an internally-threaded gear in said recess, a threaded lift member projecting

through said gear and having its lower end 5 slidably engaged with said guideway in the standard, and an operating-lever loosely pivoted on the side of the standard-neck below said gear, a loosely-mounted pinion in mesh with said gear and a double-armed pawl in said lever engaged with said pinion.

2. In lifting-jacks, a standard having a spindle rigidly affixed at one side thereof, a threaded lift member and drive-gear therefor mounted upon said standard, an operating-lever sleeved upon said spindle between the standard and said drive-gear and held in operating position thereby, a pawl on said lever 15 adapted to operatively engage said drive-gear, and a crank rigid with said drive-gear at the outer side thereof.

3. In lifting-jacks, a lifting-screw and a threaded miter-gear to operate the same, a

hollow standard for said parts and a spindle 20 secured to one side of said standard, a compound bevel and spur gear free to rotate on said spindle and meshing with said miter-gear and having an integral crank at its outer side, a lever sleeved upon said spindle and 25 having bearing engagement therewith at the inner end thereof nearest to the center of rest of said standard and on the inside of said drive-gear, and a double-acting pawl on said lever adapted to engage said compound bevel 30 and spur gear.

In testimony whereof I sign this specification in the presence of two witnesses.

JOHN H. BURKHOLDER.
